GEORGE C. JENSEN, OF OAKLAND, CALIFORNIA.

ENGINE-LOCKING DEVICE.

1,262,199.

Specification of Letters Patent. Patented Apr. 9, 1918.

Application filed January 22, 1917. Serial No. 143,545.

To all whom it may concern:

Be it known that I, GEORGE C. JENSEN, a citizen of the United States, residing at Oakland, in the county of Alameda and State of California, have invented certain new and useful Improvements in Engine-Locking Devices, of which the following is a specification.

The present invention relates to a locking mechanism for engines and more particularly of a mechanism for coöperating with the engine controlling valves and which is capable of locking all or certain of said valves from movement, preferably in their raised or lifted position, thus preventing the compressing of a fuel charge within the cylinders and thereby maintaining the engines inoperative.

The principal objects of the invention are, to provide a lock controlled mechanism which is capable of operative movement to engage the engine valves and to lock the same to prevent the operation of the engine, one which is capable of being locked in its operative position thereby preventing the operation of the engine by its own power, and one wherein certain elements are automatic in their operation of engaging and releasing from the valves on the actuation of said lock controlled mechanism.

The invention is particularly adapted for use in connection with internal combustion engines in general, either when used for marine purposes, vehicles, or for stationary purposes, the main object being to provide a lock controlled means for preventing the compressing of the gas charge within the cylinders thereby rendering the operation of the engine under its own power impossible.

With the above mentioned and other objects in view, the invention consists, in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein,

Figure 1 is a view in side elevation partly in broken section, illustrating an internal combustion engine with the preferred embodiment of my invention applied thereto.

Fig. 2 is a sectional view taken on the line 2—2 of Fig. 1.

Fig. 3 is a sectional view taken on the line 3—3 of Fig. 2, viewed in the direction of the arrows.

Fig. 4 is a sectional view through the lock mechanism.

Referring more particularly to the several views of the drawings wherein like characters of reference designate corresponding parts, 1, indicates a suitable engine or motor of the internal combustion type, provided with the usual inlet and exhaust valves 2 and 3, operated by the respective tappets 4 and 5 actuated by the usual cams 6 and shaft 6'.

The tappets operate through guides 7, and extending laterally from certain of the guides 7 preferably the guides of the exhaust valves are the arms or bosses 8. A controlling rod 9 capable of lineal movement, is disposed longitudinally within the engine between the guides 7 and bosses 8 and the same extends to a suitable controlling station A, and that portion thereof extending from the engine is protected by a suitable tubular casing 10, disposed intermediate the station A and the point where the rod leaves the engine as in Fig. 1.

The tappets 5 associated with the valves 3 are each provided adjacent their upper end with an annular groove or seat 11, the upper surface of which is adapted to lie slightly above the upper end of the guides 7 when the tappets are in their raised position. Coöperating with each grooved tappet is a suitable locking plate 12 each pivotally secured at its outer end to one of the bosses 8 by a suitable screw or other fulcrum member 13. The free ends of the plates 12 are hooked as at 14 and are each formed with a recess 15 which is of a sufficient size to admit of the edge thereof to be received in the annular groove or seat 11 when the plates are pivoted on their fulcrum in a hereinafter described manner.

The plates 12 are each formed with an upwardly bent or stamped portion 16 providing a chamber 17 extending longitudinally over the controlling rod 9, and in each of said chambers are positioned the springs 18.

and 19 adapted respectively for moving the plates to locked or operative or unlocked or inoperative position relative to the push rods, dependent on the direction of the 5 lineal movement of the rod 9. The springs are retained in the chamber 17 preferably by bending a portion 17' of the opposite ends of the chamber walls toward each other as in Fig. 2 of the drawings.

10 Upwardly projecting from the rod 9 are the tongues 20, one extending upwardly into each chamber 17 between the adjacent ends of the springs 18 and 19 as in Fig. 2 of the drawings.

15 The lineal movement of the rod 9 inwardly relative to the engine 1, causes the tongues to exert pressure on the springs 19, which in turn force the locking plates 12 into frictional contact with their respective 20 tappets 5, and on the upward movement of the tappets to raise their coöperative valves, the tension of the respective springs 19 is sufficient to force the locking plates into engagement with the grooves 11 thereby 25 retaining the exhaust valves in their raised position and preventing the compressing of the gas charge in the cylinders, thus rendering the engine inoperative. An outward lineal movement of the rod releases the compression of the springs 19 and compresses the springs 18, the tension of which is sufficient to remove the locking plates 12 from their tappets 5 on the next slight upward movement of the same, thus permitting the 30 gas charge to be compressed within the cylinders thereby enabling the engine to operate under its own power. The grooves or sects 11 are of a width slightly in excess of the thickness of the plates 12 and are so 35 disposed as to permit of a very limited upward movement of the tappets by the coöperating cams when the plates 12 are in operative or locking position.

40 The outer end of the controlling rod is 45 preferably circular in cross section as at 20', as in Fig. 4 of the drawings and projects through a suitable casting or housing 21 positioned at the operating station A and the outer end of said rod terminates preferably 50 in a suitable handle 21'. The portion 20' of the rod is provided with a suitable flange 22 operating in a chamber 23 in the housing and said flange limits the outward movement of the rod through contact with the 55 outer wall 24 of the chamber. A suitable spring 25 surrounding the portion 20' of the rod is interposed between a wall 25' and the flange 22 and is of sufficient tension to overcome the combined tension of the springs 18 60 so that the rod will normally lie in operative or neutral position as in Fig. 4.

65 A suitable rotatably mounted key controlled locking barrel 26 is positioned in the bore 27 extending angularly from the chamber 23, and the lower end thereof is beveled

as at 28 to admit of the passing of the flange 22 beneath the same when the rod 9 is manually moved its full distance inwardly. The rotation of the barrel 26 when the rod 9 is moved inwardly its full distance causes the 70 lower end of said barrel to lie in contact with the beveled upper surface 29 of the flange 22, thus locking the rod in its operative position, the barrel being held in locked position by the usual key controlled tumblers 30. While I have illustrated a key controlled lock, it is to be understood that any suitable type of lock may be employed.

75 A manually releasable catch 31 pivoted as at 32 to the outer wall 24 of the mounting 80 21 automatically drops into a notch 33 in the upper surface of the portion 20' adjacent the handle 21' and retains the rod in its innermost position while the barrel is being operated either to lock the rod or to permit the release of the same on the actuation of the catch.

85 The locking plates 12 are preferably protected by the usual valve spring cover plates, not shown, which are fitted over the side 90 walls of the engine and said cover plates if desirable, may be locked in any suitable manner when in position, or the locking-plates 12 and portion 9 of the rod may be built into the engine at the lower end of the valve 95 tappets when the engine is manufactured, it only being essential that the plates 12 be prevented from being released by other means than through controlling springs and actuation of the rod 9.

100 It is apparent that the action of the springs 18 and 19 due to the tension placed thereon by the lineal movement of the rod 9 controls the action of the locking plates 12 in locking tappets in their raised or inoperative position or in releasing the plates from the tappets to permit the operation of the engine.

105 It will also be understood that the rod 9 may be actuated while the engine is running 110 and as the exhaust valves raise or lift the same will be automatically engaged and retained in their upper or inoperative position.

110 Having thus described my invention, what I claim is,

115 1. In combination with an internal combustion engine having the usual mechanically operated valves controlling the engine inlet and exhaust openings, of lock controlled mechanism for coöperating with 120 said exhaust valves and adapted when in operative position to lock said exhaust valves in open position.

125 2. In combination with an engine having the usual mechanically operated valves controlling the engine inlet and exhaust openings, of lock controlled mechanism for coöperating with said exhaust valves and adapted when in operative position to lock 130 said exhaust valves from movement.

3. In combination with an internal combustion engine having the usual mechanically operated inlet and exhaust valves of the puppet type, of lock controlled mechanism for coöperating with said exhaust valves and adapted when in operative position to lock said exhaust valves from movement.
4. In combination with an internal combustion engine having the usual mechanically operated inlet and exhaust valves of the puppet type, of lock controlled mechanism for coöperating with said exhaust valves and adapted when in operative position to lock said exhaust valves in their open position.
5. In combination with an internal combustion engine having the usual mechanically operated inlet and exhaust valves, devices for coöperating with the same and adapted when in operative position to lock certain of said valves from movement, and lock controlled mechanism coöperating with said devices for retaining the same in their operative position.
6. In combination with an internal combustion engine having inlet and exhaust valves, devices for coöperating with the same, and adapted when in operative position for locking certain of said valves from movement, yieldable mechanism coöperating with said devices and adapted for movement to exert pressure thereon to cause the same to move from or into operative position, and lock controlled means for preventing the operation of said mechanism.
7. In combination with an internal combustion engine having the usual inlet and exhaust valves mechanically operated during the operation of the motor, lock controlled means coöperating with certain of said valves and capable of locking the same in their open position to prevent the compressing of a fuel charge within the engine cylinders thereby rendering the engine inoperative.
8. In combination with an internal combustion engine having inlet and exhaust valves, devices adapted when in operative position for locking certain of said valves from movement, lock controlled means for operating said devices, said lock controlled means capable of operation to permit the automatic engagement or release of said device relative to said valves during their movement.
9. In combination with an internal combustion engine having inlet and exhaust valves, locking devices capable of movement to engage with said exhaust valves to lock the same in their raised position relative to the seat, a lock controlled controlling means for said devices, and a yielding connection intermediate said controlling means and said devices.
10. In combination with an internal combustion engine having inlet and exhaust valves, a pivotally mounted locking member associated with said exhaust valves, and adapted when in operative position for coöperating with said valves to retain the same in an unseated position, an operating rod for actuating said locking member and capable of movement in two directions, spring tension means interposed between said rod and said locking member whereby said member is rendered automatic in its movement from or into operative position, dependent upon the direction of operation of said rod, and means for locking said rod from movement when said locking member is in operative position.
11. In combination with an internal combustion engine having inlet and exhaust valves, a pivotally mounted locking member associated with said exhaust valves, and adapted when in operative position for coöperating with said valves to retain the same in an unseated position, an operating rod for actuating said locking member and capable of movement in two directions, spring tension means interposed between said rod and said locking member whereby said member is rendered automatic in its movement from or into operative position, dependent upon the direction of operation of said rod, means for locking said rod from movement when said member is in operative position and means for automatically operating said rod to enable the release of said locking member on the release of said locking means.
12. An apparatus for rendering an internal combustion engine inoperative under its own power, the same comprising a manually operated lock controlled member for engaging the engine exhaust valve during its movement and retaining the same locked from movement when removed from its seat.
13. An apparatus for rendering an internal combustion engine inoperative under its own power, the same comprising a device for engaging one of the engine valves during its operation and adapted when in engagement therewith to interrupt the operation of the same, and lock controlled means for controlling the operation of said device.
14. An apparatus for rendering an internal combustion engine inoperative under its own power through the locking of the valves, the same comprising a locking plate pivoted to swing on a vertical axis, a projection formed on one of the engine valves and beneath which the said plate is adapted to be received, a manually operated controlling rod associated with said plate, and a yielding connection between said rod and plate, said connection adapted on the operation of said controlling rod to exert pressure on the said plate and cause the same to lie beneath

said projection on the alining of the same with the upper surface of said plate.

15. An apparatus for rendering an internal combustion engine inoperative under its own power through the locking of the valves, the same comprising a locking plate pivoted to swing on a vertical axis, a projection formed on one of the engine valves and beneath which the said plate is adapted to 5 be received, a manually operated controlling rod associated with said plate, a yieldable connection between said rod and plate, said connection adapted on the operation of said controlling rod to exert pressure on the said

plate and cause the same to lie beneath 15 said projection on the alining of the same with the upper surface of said plate, and means for retaining said rod in locked position on the exertion of the pressure on said plate.

20 In testimony whereof I have signed my name to this specification in the presence of two subscribing witnesses.
